UNITED STATES PATENT OFFICE.

CHARLES L. GOEHRING, OF ALLEGHENY, PENNSYLVANIA.

MOLDING-MACHINE.

SPECIFICATION forming part of Letters Patent No. 394,765, dated December 18, 1888.

Application filed February 3, 1888. Serial No. 262,902. (No model.)

To all whom it may concern:

Be it known that I, CHARLES L. GOEHRING, of Allegheny, in the county of Allegheny and State of Pennsylvania, have invented certain new and useful Improvements in Molding-Machines; and I do hereby declare the following to be a full, clear, and exact description of the same, reference being had to the accompanying drawings, forming a part of this specification, and to the figures and letters of reference marked thereon.

My present invention relates to improvements upon the apparatus or form of mechanism disclosed in my application, No. 260,098, and constituting a part or portion of the main system described in another application, No. 260,097; and my said invention consists in the novel and improved combination and arrangements of the devices for effecting the oscillations of the arbor about its pivotal point of support and their co-operative relations with other parts of the system, as hereinafter described, and pointed out in the claims.

In the accompanying drawings, Figure 1 is a top plan view of the mechanism to which my present invention is applied. Fig. 2 is a longitudinal vertical section. Fig. 3 is a side elevation showing the manner of supporting and adjusting the pivot of the actuating-lever. Fig. 4 is a sectional view on line $x x$, Fig. 3. Fig. 5 is a front view of the arbor-supporting slide. Fig. 6 is a side elevation, partly in section, of a portion of the cutting mechanism, showing a driving mechanism for accommodating the various movements of the arbor.

Similar letters and figures of reference in the several figures indicate the same parts.

My present invention and improvements as applied and used in connection with the molding-machine described in my prior application relate more especially to the means for effecting and controlling the oscillations of the cutter-head, operating separately or in conjunction with devices for reciprocating said cutter-head laterally or vertically or simultaneously in both of said directions with respect to the line of movement of the material or board operated upon. As described and illustrated in said applications, the board or other material operated upon is fed or ad-

vanced positively and continuously in a right line and the several cutting mechanisms are so connected to the driving mechanism that their controlling devices shall at all times be caused to move in unison with the feed-controlling devices and at a speed proportional to the latter.

The particular variety of cutting mechanism to which this invention more particularly has reference is that employed for producing the ornamental or other designs upon the face or horizontal surface of the material, the various movements, and more especially the transverse reciprocations and oscillating movements of the cutter-head, being timed and proportioned to correspond with the reciprocations of the edging-cutter or those producing the general outline of the edges of the board. For a more detailed description of the other co-operating elements reference is made to my before-mentioned prior applications.

The letter A designates a portion of the frame-work constituting guides or ways in which the carriage B is supported, said carriage being controlled in its vertical movements by cams driven in unison with the rolls or other feeding mechanism.

The carriage B is constructed in two sections movable the one upon the other for adjusting the height of the cutting devices relatively to the cam-surfaces for raising or reciprocating the carriage. The adjustment of the two sections may be effected by a screw-connection, b, and in addition to the latter a transverse clamping-bolt, b', or equivalent device may be employed, when desired, for securing the two sections firmly in position after adjustment.

The upper section of the carriage B is provided with a top or platen, B², slotted, as at b², for the accommodation of the driving-belt, and provided with an arched brace, b³, at or near its forward end, and furnished with transverse guides or ways b⁴. Supported to reciprocate in these guides is a carriage or slide, C, formed in two sections, adjustable by a screw, c, the one upon the other, the rear end or section being provided with an abutment or roller, c', maintained in contact with an actuating-cam, C', which latter is driven in

unison with the feeding devices, as explained in connection with the lower cams.

Near the forward end of the slide C is formed an opening, c^x , to accommodate the driving-belt, and webs or strengthening-ribs c^2 are applied or formed on the slide opposite the said opening c^x .

Beneath the slide C is located the oscillating arbor-frame D, pivotally attached to said slide at or near its inner or forward end, the rear portion of said arbor-frame being supported upon a segmental or equivalent bracket or guide, d^0 .

The parts thus far described do not differ, essentially, in construction and operation from those illustrated in my beforementioned application, No. 260,098—that is to say, the arbor-frame carrying the cutter located beneath and in line with its pivot oscillates, while its supporting-frame is reciprocated transversely of the line of feed of the material, and at the same time a vertical movement is communicated to the slide by the cams acting beneath its supporting-carriage, the several movements referred to being timed and proportioned to the movements of the feeding devices and the passage beneath the cutters of the material to be operated upon.

The arbor-frame D is provided with bearings d , supporting the arbor D', the pulley d' being located between said bearings and the cutter-head D² beyond the outer bearing and beneath the pivotal point, so as to bring the principal cutter in the center of oscillation; and in order that the cutter-head may be adjusted with respect to this center of oscillation the pin or pivot E, for connecting the arbor-frame and its supporting-slide, is adjustably attached to the arbor-frame—as, for example, by forming a T-groove, e , in said frame and inserting therein the head of bolt E. In order to afford a better support for the cutter-shaft D' and prevent it from springing, I mount a bearing, d^2 , on the forward extension of arbor-frame D and apply it to the arbor beyond the cutter-head, as shown, thus providing three bearings for the arbor—one at each end and the third between the pulley and cutter-head—said bearings being located on the side of the arbor to which the most pressure is applied—that is to say, opposite the material to be operated upon and upon the side toward the driving-pulley—and in order that the cutter-head may be conveniently taken off, inspected, and replaced the said outer bearing is detachably and adjustably secured to the arbor-frame D.

To the pin E is secured an arm, 1, to which the actuating devices for controlling the oscillations of the arbor-frame are attached, and in order that said arm may be securely clamped upon said bolt and the latter at the same time be firmly attached to the arbor-frame a sleeve, 2, is interposed between and bears at opposite ends against the arm 1 and arbor-frame or washers resting thereon, and the pivot-bolt E passes through said sleeve and is clamped and

held in position by a detachable or adjustable device—such as a nut, 4—whereby the arm 1 and arbor-frame may be secured together by the bolt and clamped upon the sleeve 2 without producing excessive frictional contact with the slide C, as no matter how much pressure is brought to bear to clamp these parts together the sleeve 2 will turn freely in its bearing in slide C.

To the arm 1, preferably secured in a position parallel with the arbor, is pivotally attached a link, 5, whose opposite end is pivoted on a lever, 6, fulcrumed, as at 7, and bearing against the outer end of a bar, 8, mounted in ways upon the carriage B, with its inner end in contact with the cam C'. The connections between the link 5 and arm 1 and lever 6 are preferably made adjustable, and the fulcrum pin or bolt 7 is made adjustable both longitudinally and laterally of the lever 6 to provide for variations and changes in the proportions of the levers and the angular position of the parts. Thus, in the illustration given of these features the pins 10, upon which the link 5 is pivoted, are made adjustable in slots 11 in the arm 1 and lever 6, while the pin 7 is adjustably secured in a slot, 12, formed in a bracket, 13, the latter supported in ways 14 on the carriage B and moved for adjustment by a screw, 15. The angular position of the lever 6 may, moreover, be adjusted or fixed through the instrumentality of the pivoted bearing 16 and screw 17; but these elements are mainly employed for a different purpose—that is to say, to compensate for the longitudinal movement of the bar 8 upon the lever, for as said bar is reciprocated in a line tangential to the arc in which the lever oscillates the point of contact is constantly shifted, tending to increase or diminish the leverage and in proportion thereto the speed; but by providing an inclined surface for the bar to act upon and properly proportioning the angle of inclination to the lateral movement of the point of contact the variation in speed will be compensated for and the lever caused to oscillate with a practically uniform speed.

Any suitable form of driving mechanism competent to accommodate the various movements and adjustments of the arbor may be employed for driving the cutter-head while the latter is being reciprocated. In Fig. 6 I have illustrated one form of mechanism of this character, the same consisting of a yoke or frame, p , movable vertically in guides p' , and held elevated by a yielding tension device, such as weight p^9 and lever p^7 . The yoke p is provided with bearings for a shaft, p^2 , held parallel with and above slide C, said shaft carrying a parallel faced pulley, p^3 , and a crown or convex pulley, p^6 . The pulley p^4 on the arbor is crowned, and belt p^5 , encircling pulleys p^3 and p^4 , is caused to traverse the wider pulley, p^6 , as the slide C reciprocates.

The driving-pulley (shown in dotted lines) is carried by a shaft to one side of shaft p^2 , and a belt connects said driving-pulley and pulley

p⁶. The vertical and lateral movements of the arbor-frame are compensated for by the vertical play of the yoke.

5 The method of producing figures and signs on the surface of wood and other materials referred to herein and to which this invention relates is claimed in another application, Serial No. 282,590.

Having thus described my invention, what I 10 claim as new is—

1. In a machine such as described, wherein an overhung arbor-frame is pivotally attached to its support, so as to oscillate thereon, and in combination with said frame provided with 15 an opening for the passage of the driving-belt, an arbor carrying a pulley and a cutter-head and supported at each end and between the cutter-head and pulley in bearings attached to the arbor-frame on the side next the 20 material to be operated upon, substantially as described.

2. In combination with the oscillating arbor-frame, the arbor carrying cutter-head and pulley and supported in bearings on opposite 25 sides of the pulley and at a point beyond the cutter-head in a detachable bearing in the overhanging portion of the arbor-frame, substantially as described.

3. In combination with the arbor-frame pivotally supported and extended beyond the center of oscillation, the arbor supported in bearings upon said frame and in a plane transverse to but intersecting the pivotal center, said bearings being mounted upon the arbor-frame and supporting the arbor on both sides 35 of the cutter-head and pulley, substantially as described.

4. In a machine such as described, and in combination with the reciprocating slide and 40 the oscillating arbor-frame pivotally mounted on the former, a lever connected to said oscillating frame and actuated by a slide and cam to control the oscillations of said arbor-frame, substantially as described.

45 5. In combination with the slide and its actuating-cam, the arbor-frame pivotally connected to said slide, a lever connected by a link to the pivotal support of the arbor-frame, and a reciprocating bar engaging said lever 50 and actuated by a cam to control the oscillation of the arbor-frame, substantially as described.

6. In combination with the reciprocating slide and its actuating devices, the arbor-frame carrying arbor, pulley, and cutter-head 55 pivotally secured to the overhanging portion of said slide, an arm secured to the pivotal support for the arbor-frame and connected to a lever, and a reciprocating bar actuated in 60 unison with the devices controlling the movements of the slide and engaging said lever, substantially as described.

7. In combination with the slide overhanging the work-support, the arbor-frame adjustably attached to said overhanging portion by 65 pivotal connection, an arm secured to said pivot, an actuating-lever, a link interposed

between said arm and lever, and devices acting upon said lever to cause it to oscillate, substantially as described.

8. In combination with the oscillating arbor-frame, the slide or support upon which it is mounted, and the arm through which motion is transmitted to said arbor-frame, a sleeve or thimble passing through the support 75 and abutting against said arm and arbor-frame, and a bolt passing through said sleeve and engaging both the arbor-frame and arm to secure them in position and clamp them upon the sleeve, substantially as described. 80

9. In combination with the slide projected over the work support or table, the arbor-frame pivotally attached to the said overhanging portion of the slide, and the arm for actuating said arbor-frame, a bolt adjustably 85 secured to the arbor-frame and engaging the arm, and a sleeve or thimble surrounding the bolt and interposed between the arbor-frame and arm, said sleeve being journaled to the support or slide, substantially as described. 90

10. In a machine such as described, the combination, with the reciprocating slide and its actuating-cam, of the arbor-frame pivotally attached to said slide, a lever connected to the pivot on which the arbor-frame oscillates, 95 and a reciprocating bar engaging said lever and driven from the same cam that actuates the slide, substantially as described.

11. In a machine such as described, the combination of the movable carriage, the reciprocating slide mounted thereon, the oscillating arbor-frame carrying arbor and cutter-head pivotally attached to said slide to reciprocate in unison therewith, a lever fulcrumed upon the carriage and connected to 100 the arbor-frame for oscillating the latter, a bar supported in ways upon the carriage, and actuating devices engaging said bar and the reciprocating slide to cause them to move in unison and proportionally, substantially as 105 described.

12. In combination, the oscillating arbor-frame, its support and the bolt forming a pivotal connection, an arm secured to said bolt and connected to an operating-lever, the latter mounted upon an adjustable fulcrum, and operating devices engaging said lever to oscillate the arbor-frame, substantially as described. 115

13. In combination with the oscillating arbor-frame and the arm and link attached thereto, a lever provided with an inclined face and a reciprocating bar engaging said inclined portion, substantially as described.

14. In a machine such as described, and in combination with the oscillating arbor-frame and the actuating-lever connected thereto, the adjustable bearing-block 16 and the bar reciprocating in ways and engaging said adjustable block, substantially as described. 120

15. In a machine such as described, and in combination with the lever connected to and actuating the oscillating arbor-frame, the adjustable fulcrum on which said lever is

mounted, the reciprocating slide for engaging said lever to oscillate the arbor-frame, and the pivoted and adjustable bearing interposed between said lever and bar, substantially as 5 and for the purpose set forth.

16. In a machine such as described, the combination of the carriage provided with an opening for the passage of the driving-belt, a 10 slide reciprocating in ways on the carriage and extended beyond said opening, and provided with a corresponding opening or space for the driving-belt, the oscillating arbor-

frame mounted beneath said slide, the arbor supported in bearings on said frame, the cutter-head located between the work and the 15 pivotal point of attachment to the slide and in line with said pivot, and the pulley, also mounted on said arbor and beneath the supporting-slide, substantially as described.
